UNITED STATES PATENT OFFICE.

HENRY WATERSON, OF NEW YORK, N. Y., ASSIGNOR TO DAVID GRIMES INC., OF JERSEY CITY, NEW JERSEY, A CORPORATION OF NEW YORK.

DESIGN FOR A CABINET FOR RADIO RECEIVING SETS.

Application filed July 25, 1925. Serial No. 14,227. Term of patent 7 years.

To all whom it may concern:

Be it known that I, HENRY WATERSON, a citizen of the United States, residing at 381 Park Avenue, in the city and county of New York, borough of Manhattan, and State of New York, have invented a new, original, and ornamental Design for Cabinets for Radio Receiving Sets, of which the following is a specification, reference being had to

the accompanying drawings, forming part thereof, of which—

Figure 1 is a front elevation of a cabinet showing my new design, and Figure 2 is an end view thereof.

I claim:

The ornamental design for a cabinet for radio receiving sets as shown.

HENRY WATERSON.
